MIXING DEVICE

William A. McLean, Geneva, N. Y.

Application July 2, 1941, Serial No. 400,754

7 Claims. (Cl. 259—24)

This invention relates to mixers and to like devices for obtaining thorough mixing, emulsification or dispersion of liquids and fluids having a wide viscous range. The invention deals more particularly with constructions for adjustably supporting the mixing elements of mixing devices and contemplates constructions equally applicable to beaters, grinders and the like.

Reference is made to Patent No. 2,250,838, dated July 29, 1941, in which the type, purposes, and mode of operation of mixing devices herein contemplated are fully set forth, the present invention presenting improvements thereover.

An object of the invention is to provide a mixing device having novel means for adjustably supporting the mixing elements of such devices whereby a structure having a wide variety of applications, is obtained.

Another object of the invention resides in the provision of mixing devices in which circulation, in addition to that imparted by the mixing elements, is obtained to shorten the mixing period.

A further object resides in the provision of mixing devices wherein the circulatory path of the materials being mixed may be controlled with respect to the level of such materials in the vessel in which the mix occurs to obviate circulation intimate to the mixing elements of the devices.

A still further object is to provide improved simple and novel means for adjustably mounting mixing devices of the indicated character upon drums, tanks, or similar vessels.

The foregoing objects and other objects, features and advantages of the invention will be more clearly evident from the following detailed specification in which several preferred forms of the invention are described, said specification being based on the accompanying drawings, in which—

Fig. 1 is a vertical sectional view of a mixer embodying features of the invention.

Figs. 2, 3, and 4 are horizontal sectional views taken respectively on the lines 2—2, 3—3, and 4—4 of Fig. 1.

Figs. 5, 6, and 7 are fragmentary vertical sectional views showing alternate forms of the invention.

Referring to the drawings in greater detail and with particular reference to Figs. 1 to 4, the mixer is shown as applied to a vessel such as a drum or tank 10 of standard design and size. Such vessels, round in plan, vary somewhat in their dimensions. Provision is, therefore, made

for adjustably securing the mixer firmly to such standard but varying vessels.

To this end, the mixer support plate 11, which is designed to rest upon the top of the drum 10, may be provided with a plurality of members such as the lugs 12, adjustably mounted in radial slots 13 formed in the support plate, and adapted to be locked as by nuts 14. By moving the lugs 12 into intimate contact with the inner surface of the drum wall, the support plate 11 is effectively mounted against inadvertent displacement during operation of the mixer.

In the form of the invention under discussion, the support plate is provided with two or more seats 15 in which are supported means such as the posts 16, the latter being adapted to be adjustably clamped in said seats as by means of clamp screw means 17.

The support posts 16 are preferably connected with a motor mounting plate 18 upon which the electric motor 19 is set.

In the above simple and effective manner, the motor 19 is adjustably secured on the support plate 11 which, in turn, is secured to the drum 10.

The mixer is provided with a rotor 20, mounted on a vertically disposed shaft 21, to which is secured a coupling 22 as by means of a set screw 23. Said coupling 22 is preferably connected to the motor shaft 24 as by means of the key connection 25.

It is evident that rotation of the motor shaft will be imparted to the rotor 20 which comprises one of the mixing elements.

Inasmuch as the coupling 22 (and thus the rotor 20) is longitudinally movable with respect to the motor shaft 24, means are provided to support the same. In the present instance, this means comprises an anti-friction bearing 26 arranged in a seat 27 formed in the support plate 11. This bearing is preferably both of the radial type to provide for ease of rotation of the shaft 21 therein and of the thrust type to counteract the downward pull of the rotor 20. Should, however, the rotor be of the upward thrusting type, the bearing seat 27 may be reversed as can be understood.

From the above it may be seen that the mount for the rotor is independent of the motor mount, the sliding connection between the coupling 22 and the motor shaft 24, permitting this arrangement.

The other mixing element, such as the stator 28, is preferably supported from the shaft 21. For this purpose, said shaft is preferably shouldered as at 29 to support the inner race of a radial-thrust anti-friction bearing 30 disposed in

a seat 31 formed in a support frame 32. An adjustable abutment, such as the collar 33, may be mounted on the shaft 21 to support said support frame 32, the latter being connected with the stator 28 as by means of tie-bars 34. As shown in Fig. 4, the tie-bars may be provided with blades, paddles, fins, or the like 35 for the purpose of inducing additional circulation to the material being mixed in the vessel 10.

When setting up the device, the collar 33 is placed to provide the desired gap between the rotor 20 and the stator 28. It will be noted that the seat 31 is so formed as to permit limited vertical upward movement of the frame 32 and thus of the stator 28, a condition which occurs when the viscosity of the material being mixed increases during mixing.

In the operation of the device, the circulation of the materials would be quite intimate to the mixing elements 20 and 28 and would only cause a relatively slow induced flow in the materials thereabove. In order to hasten the time of mix, the stator inlet may be heightened as by means of a hollow column 36. This column may be of a height so that its top opening is somewhat below the level of the materials in the vessel. Thus the flow induced by the mixing elements takes place throughout the entire mass of the materials, the circulation being from the lower portion of the mixer mouth at 37 upward along the walls of the drum 10 and then downward into the top of the column 36.

Because of the manner in which the stator is mounted, said stator will be rotated by the motor driven rotor, said rotation being imparted by the frictional engagement of the materials passing between the mixing elements 20 and 28. This rotation will cause the mentioned additional mass circulation by the means 35.

For a clearer understanding of the mode of operation and the uses of a mixer as above described, reference is again made to application Serial No. 310,073.

An alternate form of the invention is shown in Fig. 5. In this form the support frame 32 is omitted and the motor support posts and the tie-rods combined as leg supports 40. Thus constructed, the stator is held against rotation but may be adjusted with respect to the bottom of the mixing vessel by the clamp screws 17. The spacing between the mixing elements may be adjusted and set in a manner somewhat different from that shown in Fig. 1. The bearing 26^a, a counterpart of the bearing 26 is supported in a seat 27^a in a cup or the like 41. The latter is preferably provided with arms 42 which are formed with eyes 43 engaged over the leg supports 40. Means such as clamps or set screws 44, for adjustably locking said eyes to said supports, may be provided. In other respects the structure follows that of Fig. 1.

The cup 41, arms 42 and eyes 43 form a support member for the rotor shaft 21 and may be adjusted vertically on the leg supports 40 to obtain a desired clearance between the mixing elements 20 and 28.

Instead of the support member being carried by the leg supports, said member may comprise a bearing housing 45 threadedly engaged in the support plate 11^b. This construction is shown in Fig. 6 wherein the support legs 40 are pinned to said support plate and are not vertically adjustable because of the limited vertical adjustment capable of being made for the rotor shaft 75

21 by manipulation of the bearing housing 45.

However, the structures of Figs. 5 and 6 may be combined in the structure of Fig. 7 wherein the bearing housing 45 may be threadedly engaged in the cup 41. The latter is similar to the cup 41 and is provided with the arms 42 and eyes 43 as described. By this structure the entire mixer assembly may be adjustably mounted with respect to the bottom of the mixing drum and the gap between the mixing elements may be adjusted by manipulation of the bearing housing 45.

In previous designs the entire weight of the mixer was carried by the motor shaft. In the constructions disclosed, this weight is either carried by the support plate 11 or 11^b or the leg supports 40. The structure lends itself to being designed for a stator having induced rotation or for one which is fixed against rotation. Further, the structure may readily be made to afford a variable gap between the mixer elements as in Fig. 1 or to maintain a fixed yet adjustable gap as in the other disclosed forms of the invention. If desired, the hollow column 36 may be perforated to permit limited flow of the mass into intermediate portions thereof.

From the foregoing it is evident that devices incorporating the principles of the invention may be made despite changes in the form and arrangement of the parts thereof. Such changes are contemplated within the spirit and scope of the invention and it, therefore, should be understood that the specific forms herein disclosed are intended as exemplary only.

What I claim as new and desire to secure by Letters Patent is:

1. A mixer or like device comprising an electric motor, support means for said motor, a mixing element, means connecting said mixing element and said motor for driving the former, a support bearing for said latter means carried by said support means, and means for adjusting the position of said support bearing with respect to said support means.

2. A mixer or like device comprising a support means, a motor mounted on said support means, a mixing element, means connecting said element and said motor for driving the former, a support bearing for said connecting means carried by said support means, a second mixing element cooperating with the first mixing element, and adjustable means carried by said support means for variably positioning said second mixing element with respect to the first mixing element.

3. A mixer or like device comprising an electric motor, a support plate, support legs between said motor and said plate, a mixing element, means connecting said motor and said mixing element for driving the latter, a support member adjustably connected to said legs, and a bearing carried by said member for supporting said connecting means and said mixing element.

4. A mixer or like device comprising an electric motor, a support for said motor comprising a support plate and posts adjustably mounted on said support plate, a mixing element, means connecting said motor and said mixing element for driving the latter, and a support bracket adjustably mounted on said posts and provided with a bearing for supporting the mentioned connecting means.

5. A mixer or like device comprising an electric motor, a support plate, support legs between said motor and said plate, a mixing element, means connecting said motor and said mixing elements for driving the latter, a member adjustably car-

ried by said support plate and a bearing carried by said member for supporting said connecting means and said mixing element, said latter member comprising a bearing cup having threaded engagement with said support plate and adjustable vertically with relation thereto.

6. A mixer or like device comprising an electric motor, a support for said motor, a mixing element, means connecting said motor and said mixing element for driving the latter, a support bracket adjustably carried by the motor support, a member threadedly engaged in said bracket and adjustable vertically in relation thereto, a

bearing in said member for supporting the mentioned connecting means.

7. A mixer or like device comprising an electric motor, a support plate, support legs between said motor and said plate, a mixing element, means connecting said motor and said mixing element for driving the latter, a support bracket adjustably mounted on said support legs, a member threadedly engaged in said bracket for vertical adjustment in relation thereto, and a bearing carried by said member for supporting said connecting means and said mixing element.

WILLIAM A. McLEAN.
